UNITED STATES PATENT OFFICE.

JOHN HENRY BELL, OF SUNDERLAND, ENGLAND.

STANCHION FOR SHIPS.

SPECIFICATION forming part of Letters Patent No. 449,994, dated April 7, 1891.

Application filed September 17, 1890. Serial No. 365,220. (No model.) Patented in England February 5, 1890, No. 1,912.

To all whom it may concern:

Be it known that I, JOHN HENRY BELL, a subject of the Queen of Great Britain and Ireland, and a resident of Sunderland, in the county of Durham, England, have invented certain Improved Stanchions for Ships' Hand-Rails and the Like, (for which I have obtained a British patent, No. 1,912, dated February 5, 1890,) of which the following is a specification.

This invention relates to improved stanchions for ships' hand-rails and the like.

My improvements consist in the production of a novel form or section of metal stanchion having for its object a new article of manufacture possessing qualifications superior to those hitherto in use in respect of relative cost of manufacture and general utility.

In the accompanying drawings, Figures 1 and 2 are side elevations of a portion of the improved metallic stanchion. Fig. 3 is a transverse sectional view of the same. Fig. 3^a is a view similar to Fig. 3 on a larger scale. Fig. 4 is an edge view of the stanchion, showing portions of rails connected therewith. Fig. 5 is a side elevation of the stanchion, showing the rails applied thereto. Fig. 6 is a sectional view taken on the lines A A, Figs. 4 and 5. Fig. 7 is a side elevation of the stanchion, showing a modified construction of hand-rail and shoe or foot-piece applied thereto. Fig. 8 is a broken edge view of the same. Fig. 9 is a top plan view of the same. Fig. 10 is a side elevation of the stanchion, showing a modified construction with the rails in section. Fig. 11 is an edge view of the same, showing portions of the rails. Fig. 12 is a sectional view taken on the lines B B, Figs. 10 and 11. Figs. 13 and 14 are sectional views illustrating modifications of form or shape of stanchion-bar as compared with the form or shape shown in Figs. 3 3^a, and hereinabove referred to.

Throughout this description like numbers of reference indicate like parts in the specification and in the drawings.

In Figs. 4, 5, and 6 the stanchion-bar 1 has a fore-and-aft flange 2 welded onto its upper end to take the rail 3, which may very conveniently be of the type or section shown in these

figures. The rail is shown connected to the stanchion-flange by countersunk rivets. The base of the stanchion is shown fitted into a special metal foot-piece or shoe 4, where it can be secured by a cotter 5, and I form the foot-piece or shoe with a channel 6 at either side thereof, so that any water getting thereinto may at once find an escape. The rails 7 pass through the web 8 of the stanchion and may be clunk over at a terminal stanchion, as shown in the figures.

In Figs. 7, 8, and 9 is shown a different type or section of hand-rail 9, riveted to fore-and-aft flanges, as hereinabove described, and instead of the metal shoe at the base of the stanchion 65 a foot-flange 10 is shown welded to the stanchion-base. In other respects Figs. 7, 8, and 9 resemble Figs. 4, 5, and 6, already described.

In Figs. 10 and 11 is shown another mode of forming the tops of the stanchions to take 70 the top hand-rail. I obtain this form by cutting out a portion of the web at the stanchion top and using the convex sides of the stanchion to form the head 11 by bringing them together and then welding and swaging them to the form shown in these figures. At the points where the rails pass through the stanchions I form a bead 12 on the convex sides of the stanchion, thus giving a neat finish to the work. In these figures foot-flanges are shown welded to the stanchions, as in Figs. 7, 8, and 9.

In Figs. 13 and 14 are shown certain modifications of type or design of section for stanchions. The application of these forms 85 being similar to that of the forms already described, further explanation in respect thereto is unnecessary.

As compared with the stanchions hitherto in use my improved stanchions possess several important advantages.

Hitherto it has been customary to form bulbs or enlargements on the stanchions, through which bulbs or enlargements the rails have been passed. By this system the 95 labor in holing the bulbs for the rails is very great, as the holing is performed through the thickest portions of the stanchions, whereas according to my system the holing is done through the web of the stanchion, which, as 100

shown in the drawings annexed hereto, is comparatively thin, and at the same time I produce a stanchion which by its convex surfaces and design of section possesses a circular and symmetrical appearance combined with lightness and strength. Moreover, I form the stanchion-bars, by preference, in rolling-mills, and from the long lengths of bars thus readily obtained I saw the stanchions to the requisite lengths and then hole them, thus producing a superior article at a relatively-reduced cost. Where desirable the bars may be passed through planishing-rolls after being sawed and holed in order to give a better finish to the stanchions.

The sections hereinabove described are especially useful in ship-building and in general construction as columns, and they may with advantage be used in, for example, ladder-stanchions, the rungs being passed through the web of the stanchion and clunk over in the usual way.

Where desirable the stanchions hereinabove described may be formed with a slight taper on them; but as this more or less complicates their manufacture in rolling-mills,

and as the result obtained by this process hardly warrants the increased cost, I prefer to manufacture rolled stanchions with parallel sides and to cast the stanchions where they are required to be tapered.

Having now particularly described and ascertained the nature of this invention and in what manner the same is to be performed, I declare that what I claim, and what I desire to secure by Letters Patent, is—

A metallic stanchion consisting of a web 8, joined to vertical sides having opposite convex surfaces, provided at the lower end with a supporting and attaching foot-piece or shoe 4, and formed at the upper end to receive and sustain the top rail 3, said web serving to support the rails 7, substantially as described and shown.

In testimony whereof I have signed my name to this specification in the presence of two subscribing witnesses.

JOHN HENRY BELL.
